UNITED STATES PATENT OFFICE.

WESLEY ARMSTRONG, OF NORTH BATTLEFORD, SASKATCHEWAN, CANADA.

ELEVATOR EQUIPMENT.

1,234,554.

Specification of Letters Patent. Patented Nov. 12, 1918.

Application filed February 28, 1918. Serial No. 219,668.

To all whom it may concern:

Be it known that I, WESLEY ARMSTRONG, a subject of the King of England, residing at North Battleford, in the Province of Saskatchewan and Dominion of Canada, have invented new and useful Improvements in Elevator Equipments, of which the following is a specification.

The invention relates particularly to an equipment for elevators wherein the doors of the elevator shaft are controlled by the car.

The invention seeks to provide as its principal object a means whereby the doors opening into the elevator shaft from various floors may be secured against opening except when the floor of the car is level with any of the floors on to which the doors open.

Another object of the invention is the provision of means to prevent the operation of the car after a door has been opened as a result of bringing the car to the level of any particular floor.

Still another object of the invention is the provision of an electrically operated apparatus conjoined with the car and with the elevator shaft doors of the several floors of a building, whereby the principal objects of the invention are contained.

Still another object of the invention is to provide an equipment of this character which is simple in construction, which is easily installed and which is cheap and may, therefore, be employed at a small cost.

Other and further objects will appear as the invention is set forth in detail in the accompanying description.

To the exact construction herein shown and described, the invention is not to be restricted. The actual practical application of this equipment may show certain desirable changes or alterations to be advisable and these the right is claimed to make, in so far as they may be compatible with the spirit of the subjoined claims.

45 In the accompanying drawings:

Figure 1 is an elevation, partly diagrammatic, of the elevator shaft and its attendant car, showing the employment of the improved equipment.

50 Fig. 2 is a detail view of a portion of the equipment which is applied on the frame of the elevator shaft door.

Fig. 3 is a detail view of an upper corner of one of the doors.

Fig. 4 is an end view of the structure shown in Fig. 3.

Fig. 5 is a view partly in section showing a portion of the equipment carried by the car and also a portion of the equipment mounted in the shaft.

Fig. 6 is a view of the same structure shown in Fig. 5 as it appears when looking at right angles to the direction in which Fig. 5 is viewed.

Fig. 7 is a view looking at Fig. 5 from the top.

Fig. 8 is a central vertical sectional view of one of the locking mechanisms employed in locking the various doors.

Fig. 9 is a view partly in section and partly in elevation showing the mechanism for locking the car against operation.

Referring to the drawings, there is shown an elevator shaft 1 communicating with the several floors 2 of a building. Each floor 75 is provided with a door 3 that communicates with the elevator shaft, these doors being slidably supported in front of the door opening on a suitable track from which they are swung by the hangers 4. The doors 3 are 80 hung in the elevator shaft and are of slightly larger dimensions than the door openings which are indicated by dotted lines in Fig. 1.

With particular reference to Fig. 1, the doors are intended to be opened by moving 85 them to the left and the equipment comprising a part of this invention and which is designed to be attached to the doors is carried on the front ends thereof which, as shown in Fig. 1, is on the right.

The surrounding frame 5 on each door opening is provided with a tripping member 6 mounted near the upper right hand corner, it being assumed that the equipment as it is being described is being viewed from 95 within the elevator shaft. This tripping member 6 is of the shape shown in Figs. 1 and 2 and is fixed pivotally to the frame 5 by means of a suitable rivet or pin 7 which passes through it at the left hand end and 100 enters the door frame. The tripping member 6 is designed to lie horizontally and it is provided with a diagonal edge 8 and a vertical edge 9 at the right hand end, this right hand end being in close proximity to the 105 right hand side of the frame 5. A pin 14 is fixed in the frame 5 and the diagonal edge 8 rests on this pin, thus holding the tripping

member 6 in the horizontal position before referred to. The purpose of this tripping member will be later described.

Each of the doors 3 carries pivotally supported thereon near the upper right hand end a shifter lever 10 which is held on a suitable pin or rivet 11 fixed in the door. The normal position of the lever 10 is vertical, this normal vertical position being obtained through the instrumentality of the pin 12 being fixed in the door 3 at a point below the pivot 11 and the flat spring 13 which is also fixed to the door 3 and presses upon the lever 10 at a point above the pivot 11. Both the pin 12 and the spring 13 stand on the same side of the lever 10 and therefore insure its remaining normally vertical but permitting it under stress of pressure applied to the top end of the lever to move on the pivot 11 against the pressure of the spring 13. The manner in which the lever 10 is mounted means, of course, that the movement of the lever is such as to shift the lower free end of the lever out beyond the right hand side of the door. The upper end of the lever 10 projects far enough above the top of the door 3 to be brought into contact with the vertical edge 9 of the tripping member 6 when the door is being closed.

The lower end 18 of the shifter lever 10 is curved outwardly from the face of the door and on the right hand side thereof is formed with a diagonal curvilinear portion 15, this portion 15 pointing back toward the face of the door. The purpose of this lever 10 is to coöperate with the tripping member 6 to effect the operation of mechanism yet to be described.

Suitably mounted on the door frame 5 at the top and on the left hand side of the latter, there are solenoids 16 which are provided with plungers 17 that are square in cross section, so that they may be precluded against relative angular movement in the solenoids. The tops of the doors 3 are provided with apertures 19 which align with the plungers 17 when the doors are in their closed position and these plungers are adapted to drop into the apertures 19 and thus prevent the opening of the doors, they having been once closed. The bottom ends of the plungers 17 are beveled in the direction of the free ends of the doors, leaving the pointed portions 20 to facilitate the entrance of the plungers into the apertures 19 when the doors are being closed.

A member for effecting the operation of the electrical equipment connected with the device is carried by the car which, as a whole, is designated by the numeral 21. This member comprises a bolt 22 inserted through one side of the car. If the car be of wood the bolt 22 may be permitted to pass through the side without the use of means for insulating it therefrom, since wood is a sufficient insu-

lafor for the purpose of this invention. If, however, the car be of steel, insulation of the bolt 22 is necessary. An arm 23 is fixedly connected to the bolt 22 exterior to the car and this arm carries at the end remote from 70 that which is connected to the bolt 22, a bolt 24 which is fixedly attached to the arm. This bolt 24 carries a roller 25 made of fiber or some other suitable insulating material and this roller is rotatably mounted on the 75 bolt. There is also mounted on the stud 24 at the opposite end from where it connects with the arm 23 and so that the roller 25 may rotate between it and the arm a contact arm 26 whose free end is bifurcated so 80 as to provide two spring clips 27 whose purpose will be later described.

The arm 23 is pivotally movable on the bolt 22 but this pivotal movement is not free and is accomplished only by overcomes 85 the friction of the friction washer 28 which is in surrounding relation to the bolt and interposed between the side of the car and the inner face of the arm 23. Thus the arm 23 is permitted a certain amount of 90 angular movement, it remaining in any position placed after the removal of the force which produces the angular movement.

There are positioned in the elevator shaft at suitable points, the contact plates 29 and 95 each plate 29 has a similar plate 30 coöperating with it but spaced away from it a suitable distance for the purpose of permitting the bifurcated end of the contact arm 23 to enter between and frictionally engage any 100 pair of plates 29 and 30. Both plates 29 and 30 are curved at their upper and lower ends these curved ends of each plate returning in the opposite direction from the curved ends of the coöperating plate. In this way the 105 end of the contact arm 23 is sure of being directed between the two plates and not impinging on the end of either in the event that it is not exactly in alignment with the plates.

Guides 31 are positioned on the walls of the elevator shaft above and below each pair of contact plates 29 and 30. These guides are designed to be in alignment with the roller 25 and at either end these guides curve 115 down toward the wall of the shaft so as to facilitate their engagement with the roller 25 to bring the roller up on their flat vertical surfaces, as is necessary after the roller has been engaged by the shifter lever 10 to 120 effect certain operations yet to be described.

The car 21 is equipped with the usual operating lever 32 and it is the purpose to equip this conventional frame or lever with a disk 33 mounted on the same axis with the 125 lever and rigidly connected thereto. On its periphery this disk is provided with a V-shaped notch 34 which, when the lever 32 is in a vertical position (this being assumed to be the off position of the lever), is en-

gaged by the V-shaped end of the pawl 35, the latter being slidable through a guide 36 carried within the car. A solenoid 37 is also carried within the car and this solenoid is 5 provided with a projecting arm 38 on which there is fulcrumed a lever 39 which at one end effects pivotal connection with the bottom end of the pawl 35, the end of the lever 39 being provided with an elongated hole to 10 permit its oscillatory movement at the same time that the pawl is moving vertically. The solenoid 37 is provided with the usual plunger 40 and the end of this plunger is connected to the adjacent end of the lever 15 39 by a link 41. When the solenoid 37 is de-energized, the longer arm of the lever 39 trips by gravity against the stop 42 thus bringing the pawl 35 out of engagement with the notch 34 and also raising the 20 plunger 40. When the solenoid 37 is en- ergized, it draws in the plunger 40 and thus operates to raise the pawl 35 so that it may engage the notch 34.

To provide the necessary current for the 25 equipment any suitable source of electrical supply 43 is employed and a conducting wire 44 leads from one terminal of this supply and extends throughout the length of the elevator shaft 1. Taps are taken off the 30 conductor 44 adjacent each floor through which the shaft 1 passes and these taps are connected one to each of the contact plates 29. The conductor 46 is led from the other 35 source of electrical supply and connects with the car 21 on the bottom thereof in the same way that the light and bell conductors connect with the car. By means of a conductor 47, the conductor 46 is connected with the terminal of the solenoid 37 and the other 40 terminal of this solenoid connects by means of a conductor 48 with the stud 22.

Let it be assumed that an elevator equipment provided with the present invention is in use and that all the doors of the elevator 45 shaft are closed and that all the attendant parts are in their normal positions. Let it be further assumed that the car 21 is between two floors and that the roller 25 has just passed under a guide 31. This roller 25 50 will then have such a position relative to the car and to the shaft as to bring the contact arm 26 in the position to have its bifurcated end comprising the spring clips 27 enter between the plates 29 and 30. When this arm 55 26 thus enters between the two plates, the floor of the car is designed to be level with the floor of the landing onto which the attendant door 3 of that landing opens. Previous to this condition of affairs, the door 60 was locked in the closed position because the solenoid 16 was de-energized and its plunger 17 engaged in the aperture 19 of the door thus locking the latter. When the contact arm 26 makes contact with the plate 29 (the 65 plate 30 being for no other purpose than to

insure a firm contact between the arm and the plate 29) an electric circuit will be established from the source of electrical supply 43 over the conductor 44, the solenoid 16, the conductor 45, the plate 29, the arm 70 26, the bolt 24, the arm 23, the bolt 22, the conductor 48, the solenoid 37, the conductor 47 and conductor 46 back to the source of supply 43. The solenoid 16 is thus energized 75 and raises its plunger 17 leaving the door 3 free to be opened. But the solenoid 37 is also energized at this time and, the car having been brought to a stop by the bringing of the lever 32 to a vertical position, the solenoid 37 by operating the lever 39 effects 80 the locking of this lever. The particular door 3 concerned may, therefore, be opened but the car 21 may not be moved because of the locking of the control lever 32. As the door is opened the upper end of the lever 10 85 contacts with the diagonal edge of the tripping member 6 and raises it on its pivot and the door is thus permitted to slide back on its hangers 4. The car having discharged its load, the door is closed but just before 90 the completion of the closing operation the upper end of the lever 10 is brought into contact with the vertical edge of the tripping member 6. The movement of the door then shifts this lever 10 on its pivot 11 and 95 throws the lower end of the lever out beyond the front edge of the door and brings its inclined portion 15 into contact with the inner circular edge of the roller 25. The continued movement of this lower portion 100 10 by means of this inclined portion 15 operates to withdraw the contact arm 26 from frictional engagement between the contact plates 29 and 30, since the arm 23 which carries the roller 25 and the arm 26 is permitted to be moved pivotally against the friction of the washer 28. The circuit which had previously obtained is broken by the withdrawal of the contact arm 26 from the contact with the plate 29. Therefore, the 110 two solenoids concerned are de-energized, the one dropping its plunger and locking the door, the other permitting its plunger to be raised by the dropping of the lever 39. The operation of the lever 10 results in moving the arm 23 and the other parts associated therewith into a position where the contact arm 26 will not be able to engage the contact plates 29 and 30 of the next floor at which it is desired to stop. The object of 115 the guides 31 is to re-establish the condition of affairs that existed before the operation of the lever 10 when the car is in the vicinity of the next floor where it is desired to stop, the guides 31 operate to shift the roller 120 25 and the arm 26 back into a position where the said arm may be enabled to engage the contact plates 29 and 30.

Of course, the contact arm 26 establishes a circuit at every floor which it passes but 130

if the car is not to be stopped the operating lever 32 is kept in the open position and the solenoid 37 is rendered inoperative so far as its movement of the lever 39 is concerned.

Of course, the closing operation of the door effects the shifting of the roller 25 just prior to the full closure position but when the full closure position is reached, the upper end of the lever 10 has been depressed far enough by the tripping member 6 to permit it to slide off under the vertical edge 9 and to be restored to its normal position by the spring 13.

15 It will thus be seen that the doors of the elevator shaft remain always locked and can only be opened at the time the car is in such a position as to permit the operation of the electrical device which locks the doors. It 20 will also be seen that the car is prevented, after a particular door has been once opened from being put in motion until that particular door is closed.

The invention having been described, what 25 is claimed as new and useful is:

1. In a device as set forth, the combination, with an elevator shaft equipped with doors at each landing, of a car movable in said shaft, electrical locking means for the 30 doors, electrical means for locking the car operating lever, contact plates carried in the shaft, means carried by the car for engagement with the contact plates, means for supplying current to the two aforesaid locking 35 means and to the contact plates and car carried engaging means, whereby a door may be unlocked and the car locked in position when the car is opposite a particular landing, and means connected with the doors 40 whereby the means on the car may be disengaged from the contact plates.

2. In a device as set forth, the combination, with an elevator shaft equipped with doors at each landing, of a car movable in 45 said shaft, electrical locking means for the doors, electrical means for locking the car operating lever, contact plates carried in the

shaft, an arm carried by the car frictionally engaging but pivotally connected with the latter, a roller carried by said arm, a contact member also carried by said arm and designed to engage between the contact plates, means to supply current to the aforesaid locking means and to the contact plates and contact member, whereby a door may be unlocked and the car locked in a position when the latter is opposite a particular landing, means conjoined with the doors whereby the arm on the car may be moved on its pivotal connection, and guides carried in the shaft for restoring the arm to the position it occupied previous to being operated on by the last said means.

3. In a device as set forth, the combination, with an elevator shaft equipped with doors at each landing, of a car movable in said shaft, electrical locking means for the doors, electrical means for locking the car operating lever, contact plates carried in the shaft, an arm carried by the car frictionally engaging but pivotally connected with the latter, a roller carried by said arm, a contact member also carried by said arm and designed to engage between the contact plates, means for supplying current to the aforesaid locking means and to the contact plates and contact member, whereby a door may be unlocked and the car operating lever locked in a position when the latter is opposite a particular landing, tripping members pivoted on top of the door frames, pivotally mounted levers carried by the doors, the upper ends of the levers being designed to engage the tripping members to cause the lower ends of said levers to engage the said roller and thus move the arm on its pivotal connection and disengage the contact arm from the contact plates, and guides carried in the shaft and designed to engage the roller to restore the said arm to its normal position.

In testimony whereof I affix my signature.

WESLEY ARMSTRONG.
